UNITED STATES PATENT OFFICE.

JOHN J. DOSSERT AND ELDA G. SMITH, OF SYRACUSE, NEW YORK, ASSIGNEES TO CROUSE-HINDS COMPANY, OF SYRACUSE, NEW YORK, A CORPORATION OF NEW YORK.

LAMP-SHADE HOLDER.

1,118,896.

Specification of Letters Patent.

Patented Nov. 24, 1914.

Application filed November 26, 1912. Serial No. 733,583.

To all whom it may concern:

Be it known that we, JOHN J. DOSSERT and ELDA G. SMITH, citizens of the United States, and residents of Syracuse, in the county of Onondaga and State of New York, have invented a certain new and useful Lamp-Shade Holder, of which the following is a specification.

This invention has for its object the production of a lamp shade holder which is particularly simple in construction and highly efficient and durable in use, and it consists in the combinations and constructions hereinafter set forth and claimed.

In describing this invention reference is had to the accompanying drawing in which like characters designate corresponding parts in all the views.

Figure 1 is an elevation, partly broken away, of this lamp shade holder, showing the positions of the parts when the clamping elements are in effective position. Fig. 2 is a vertical sectional view of the lamp shade holder. Fig. 3 is an inverted plan view partly in section. Fig. 4 is a fragmentary sectional view, illustrating the position of the parts when the clamping elements are released. Fig. 5 is a detail view of a clamping element.

This lamp shade holder comprises, generally, a body, clamping elements carried by the body in position to engage the lamp shade, an operating element encircling the body, and power-transmitting means between the operating element and the clamping elements.

1 is the body which is here shown as tubular to receive an incandescent electric lamp socket, and as provided with an annular flange 2 at its lower end.

3 are the clamping elements carried by the flange 2 and arranged in a circular series concentric with the axis of the body 1, each element 3 being in this form of my invention shown as angular and fulcrumed at its angle as at 4 in order to have a pivotal or rocking movement. The portions of each clamping element 3 on opposite sides of its angle extend above and below the flange 2 and the portion below the flange is arranged to move radially during the rocking movement of the element and is formed with means as a bead 5 for entering the groove usually provided at the upper ends of lamp shades or globes.

As here shown the flange 2 is provided with peripheral notches 6, and the clamping elements 3 are set into said notches, and each element is provided with notches 7 at its angle, the notches 7 opening through the side edges of the clamping elements in position to receive the projections 8 between the notches 6 of the flange 2.

9 is the operating element, and 10 the power-transmitting member connecting the operating element and the clamping elements 3. The power-transmitting member is here shown as a sleeve encircling the body 1 and movable lengthwise thereof and connected thereto by a pin 11 extending into a lengthwise slot 12 in the body 1, this pin and slot preventing turning of the member 10. Said member is provided with an inclined conical flange 13 at its lower end which extends under the upper or tail portions 14 of the clamping elements 3.

The operating element 9 encircles the member 10 and body 1 and is connected to the member 10 by screw threads. The member 9 bell or flares at its lower end and skirts the flange 2 and the clamping elements 3, and bears at its inner face against the edges of the projections 8, thus holding the elements 3 from displacement. The inner face of the bell or skirt of the element 9 bears on the edges of the projections 8 and hence the element 9 is held from axial movement downwardly. The element 9 is held from movement axially in the opposite direction by detachable means on the upper end of the body.

15 is a ring associated with the body 1 and engaging the upper end of the operating element 9 to hold said element 9 from endwise movement upwardly. The ring 15 is keyed to the body 1 in order to be held from turning movement by a pin 16 projecting from the body into a slot 17 in said ring 15.

19 is a cap threading on the upper end of the body 1 against the ring 15, the cap having a neck 20 for the entrance of the wires to be connected to the lamp socket, the neck being externally threaded for connection with the chandelier or other support or wire conduit.

In operation, upon the turning of the operating element 9 to move the power-transmitting member 10 downwardly into the position shown in Fig. 4, the clamping elements 3 will be released so that the shade

105

110

can be engaged or disengaged therewith and upon the turning of the element 9 in the opposite direction, the member 10 is moved upwardly into the position shown in Fig. 2, 5 clamping the elements 3 onto the lamp shade.

What we claim is:

1. A lamp shade holder comprising a tubular body, clamping elements carried by the body and arranged to engage the lamp shade, power transmitting means supported by the body and coacting with the clamping elements to operate the same, and an operating element encircling the body and being connected to the power transmitting means to actuate said means, substantially as and for the purpose described.
2. A lamp shade holder comprising a tubular body, clamping elements carried by the body and arranged to engage the lamp shade, a power-transmitting member movable lengthwise of the body and arranged to coact with the clamping elements to operate the same, and an operating element encircling the body, the operating element being connected to said member to move the same lengthwise of the body, substantially as and for the purpose described.
3. A lamp shade holder comprising a tubular body, clamping elements carried by the body and arranged to engage the lamp shade, a power-transmitting member movable lengthwise of the body and arranged to coact with the clamping elements to operate the same, and a rotatable operating element encircling the body, the operating element being connected to said member to move the same lengthwise of the body, substantially as and for the purpose specified.
4. A lamp shade holder comprising a tubular body, clamping elements carried by the body and arranged in a series concentric with the axis of the body at the lower end thereof, power transmitting means supported by the body and coacting with the clamping elements and being movable relatively to the body, and an operating element encircling the body and inclosing the power transmitting means and being connected to said means to actuate the same, substantially as and for the purpose described.
5. A lamp shade holder comprising a tubular body, clamping elements carried by the body and arranged in a series concentric with the axis of the body at the lower end thereof, a power-transmitting member common to all the clamping elements arranged to coact therewith, said member being movable lengthwise of the body, and an operating element encircling the body and said member and being connected to said member to move the same lengthwise of the body, substantially as and for the purpose set forth.
6. A lamp shade holder comprising a tu-

bular body, clamping elements carried by the body in position to engage the lamp shade, a power-transmitting member encircling the body and movable lengthwise thereof, means connecting said member and the body to prevent turning movement thereof of about the body, an operating element encircling the body, and the power-transmitting member, and being connected to the power-transmitting member by screw threads, and means for holding the operating element from axial movement relatively to the body and said power-transmitting member, substantially as and for the purpose described.

7. A lamp shade holder comprising a tubular body for receiving an incandescent electric lamp socket, the body having an annular flange at one end, rocking clamping elements arranged to fulcrum on the flange and having portions extending above and below the same whereby the lower portions move radially during the operation of said elements, an operating element encircling the body and skirting the flange and the clamping elements and coacting with the flange to be held from endwise movement in one direction, a power-transmitting member between the operating element and the clamping elements, said member being arranged within the operating element and coacting with the upper ends of the clamping elements, and detachable means on the upper end of the body for holding the operating element from movement in the other direction, substantially as and for the purpose specified.

8. A lamp shade holder comprising a tubular body for receiving an incandescent electric lamp socket, the body having an annular flange at one end, rocking clamping elements arranged to fulcrum on the flange and having portions extending above and below the same whereby the lower portions move radially during the operation of said elements, an operating element encircling the body and skirting the flange and the clamping elements and coacting with the flange to be held from endwise movement in one direction, a power-transmitting member between the operating element and the clamping elements, said member being arranged within the operating element and coacting with the upper ends of the clamping elements, and detachable means on the upper end of the body for holding the operating element from movement in the other direction, the operating element and the power-transmitting member being connected by screw threads, substantially as and for the purpose set forth.

9. A lamp shade holder comprising a tubular body for receiving an incandescent electric lamp socket, the body having an annular flange at its lower end, the flange

- being provided with peripheral notches, angular clamping elements supported by the flange and being arranged with their angles in the notches, a power-transmitting member encircling the body and movable lengthwise thereof and having means for coacting with the arms of the clamping elements above the flange, means for connecting said member and the body to prevent turning of the power-transmitting member, an operating element encircling the body and said member, and skirting the flange and the clamping elements, and resting on the projections between said notches in the flange, the operating element being connected to said member by screw threads, and means on the body for engaging the upper end of the operating element to prevent endwise movement thereof, substantially as and for the purpose set forth.
- 5 12. A lamp shade holder comprising a tubular body for receiving an incandescent electric lamp socket, the body having an annular flange at its lower end, the flange being provided with peripheral notches, angular clamping elements supported by the flange and being arranged at their angles in the notches, a power-transmitting member 10 encircling the body and movable lengthwise thereof and having means for coacting with the arms of the clamping elements above the flange, means for connecting the power-transmitting member and the body to prevent turning of the said member, an operating element encircling the body and said member and skirting the flange and the clamping elements, and having its inner face resting on the projections between 15 said notches in the flange, the operating element being connected to said member by screw threads, a ring encircling the body above the operating element and being connected to the body and being detachable therefrom, and a cap threading on the body against the ring, substantially as and for the purpose described.
- 10 13. A lamp shade holder comprising a tubular body for receiving an incandescent electric lamp socket, the body having an annular flange at its lower end, the flange being provided with peripheral notches, clamping elements supported by the flange, the clamping elements being arranged in said notches and formed with notches opening through their side edges in position to receive the projections between said notches in the flange, an operating element encircling the body and skirting the flange and the clamping elements, and being located to normally prevent displacement of the clamping elements from the notches of the flange, and means for transmitting the movement of the operating element to the clamping elements, substantially as and for the purpose specified.
- 15 14. A lamp shade holder comprising a tubular body for receiving an incandescent electric lamp socket, the body having an annular flange at its lower end, the flange being provided with peripheral notches, angular clamping elements supported by the flange and being arranged at their angles in the notches, the clamping elements being formed with notches opening through their side edges in position to receive the 20 projections between said notches in the flange, a power-transmitting member encircling the body and movable lengthwise thereof and having means for coacting with the arms of the clamping elements above the flange, means for connecting said member and the body to prevent turning of the power-transmitting member, an operating element encircling the body and said member and skirting the flange and the clamping elements and resting on the projections between said notches in the flange, the operating element being connected to said member by screw threads, and means on the body for engaging the upper end of the operating element to prevent endwise movement thereof, substantially as and for the purpose set forth.
- 25 15. A lamp shade holder comprising a tubular body for receiving an incandescent electric lamp socket, the body having an annular flange at its lower end, the flange being provided with peripheral notches, clamping elements supported by the flange, the clamping elements being arranged in said notches and formed with notches opening through their side edges in position to receive the projections between said notches in the flange, an operating element encircling the body and movable lengthwise thereof and having means for coacting with the arms of the clamping elements above the flange, means for connecting the power-transmitting member and the body to prevent turning of the said member, an operating element encircling the body and said member and skirting the flange and the clamping elements, and having its inner face resting on the projections between said notches in the flange, the operating element being connected to said member by screw threads, a ring encircling the body above the operating element and being connected to the body and being detachable therefrom, and a cap threading on the body against the ring, substantially as and for the purpose described.
- 30 16. A lamp shade holder comprising a tubular body for receiving an incandescent electric lamp socket, clamping elements carried at the lower end of the body, a rotatable operating element encircling the body, and power transmitting means between the operating element and the clamping elements, said means being connected to the operating element to be actuated thereby and to the clamping elements to control the operation thereof, said means being located within the operating element between said element and the body, the operating element being arranged to prevent the clamping elements from displacement, and the body having means associated therewith to prevent axial movement of the operating element, substantially as and for the purpose specified.
- 35 17. In testimony whereof, we have hereunto signed our names in the presence of two attesting witnesses, at Syracuse, in the county of Onondaga, in the State of New York, this 22nd day of November 1912.
